UNITED STATES PATENT OFFICE.

GEORGE FREDRICK WALTER, OF BROOKLYN, NEW YORK, ASSIGNOR TO AMERICAN CAN COMPANY, OF NEW YORK, N. Y., A CORPORATION OF NEW YORK.

METHOD AND APPARATUS FOR FORMING AN INTERIORLY-BEADED OR LOOPED TEARING-STRIP CAN.

Application filed March 17, 1926. Serial No. 95,272.

My invention relates to a method and apparatus for forming an interiorly beaded or looped tearing strip can.

The invention disclosed in the drawings and described in the specification of this application refers to the manufacture of a metal container, made according to the invention of John M. Young, which is the subject matter of a U. S. Patent No. 1,586,277. In this particular form of metal container a portion of the container wall is or may be bent inwardly and upwardly in a looped or other similar form of construction to provide an interior friction wall seat for an associated interior friction plug formed on the container cover, and utilized as a friction element after the tearing strip which is embodied in the container wall about the loop portion has been removed. In this type of container the cover is hermetically sealed to the upper part of the container and this construction forms a hermetic closure. The tearing strip is defined by scored lines and provided with an extended tongue which is engaged by the ordinary opening key to remove the tearing strip from the container wall by tearing the same along the score lines. After the tearing strip has been removed, the cover element is used as a reclosure, the construction of the cover permitting its frictional engagement into the looped portion of the container.

In manufacturing a container of this type it is highly essential that the inner diameter of the inwardly pressed looped portion which forms the friction wall seat be properly sized to correctly engage the cover member when the same is used as a reclosure.

One of the objects of my invention resides in providing a more simple method and apparatus than is disclosed in my prior applications, for properly sizing this inwardly pressed looped portion to an exact diametral dimension throughout its entire circumference whereby an effective frictional wall for the seating of the reclosing member is secured.

Yet another object of my invention resides in providing a simple and inexpensive method and apparatus for manufacturing the type of containers hereinbefore referred to, in a manner which lends itself to high speed production of relatively few operations and in an efficient manner, by simul-

taneously accomplishing the collapsing and sizing operations of the beaded wall of the can.

Still another object of my invention resides in the provision of a method and apparatus for the manufacture of containers as heretofore described, and particularly in the method and devices for forming looped wall portions in the can walls of varying outlines and shapes.

A further object resides in the provision of a novel apparatus for holding the can body during the loop forming operation and for ejecting the can body from the apparatus thereafter.

Numerous other objects and advantages of the invention will be apparent as it is better understood from the following description, which, taken in connection with the accompanying drawings, discloses a preferred embodiment thereof.

Reference should be had to the drawings, wherein:

Fig. 1 is a perspective view of a type of container adapted to be formed according to my invention.

Fig. 2 is a longitudinal section through a portion of a beading device, the view illustrating a container body in position and being operated upon.

Fig. 3 is a partial, longitudinal elevation and cross-section through a collapsing and sizing machine, the view illustrating the first or initial position of the container within the collapsing and sizing mechanism.

Fig. 4 is a view similar to Fig. 3 illustrating a further step in the collapsing operation.

Fig. 5 is a view similar to Fig. 3, illustrating the beginning of the discharge movement of the parts of the collapsing and sizing machine.

Fig. 6 is a view similar to Fig. 3, illustrating the container after discharge from the collapsing and sizing mechanism.

Fig. 7 is a cross-sectional view of a portion of the collapsing and sizing machine, the view being taken substantially along the line 7-7 of Fig. 3.

Fig. 8 is a cross-sectional view of a portion of the collapsing and sizing machine, the view being taken substantially along the line 8-8 of Fig. 3.

Fig. 9 is a fragmental sectional detail of a

portion of the collapsing mechanism, illustrating the position of the container previous to the collapsing operation.

Fig. 10 is a view similar to Fig. 9 illustrating the container body after the collapsing operation and with certain parts of the collapsing and sizing machine being held in one position to form a flattened double loop in the container body.

10 Fig. 11 is a view similar to Fig. 1, illustrating a container in position after the collapsing operation has been performed, this view illustrating the relative position of operating parts of the collapsing and 15 sizing machine whereby a form of looped bead is obtained, this being different from the form of the loop illustrated in Fig. 10.

Referring more in detail to the drawings and particularly to Fig. 1, the numeral 10 indicates a hollow container body of a 20 cylindrical or other form, provided with the ordinary side seam 11, and circumferentially scored lines 12 setting off a tearing strip 13, and further provided with directing score 25 lines 14 arranged at an angle to the score lines 12. The said tearing strip 13 terminates in the tongue 15 extended beyond the said side seam 11. The container is provided with a bottom member 16 and a cover member 17 doubleseamed to the container wall. The said cover member 17 is provided with a counter-sink 18, inwardly spaced from the interior wall of the container 10 when the cover member 17 is secured to the 30 same by the regular double seam 19. The container wall 10 is inwardly pressed at 20 to form an inwardly and upwardly extending loop 21, connecting with a downwardly and outwardly extending loop 22, formed in the container wall adjacent and beneath the tearing strip 13. The inner diameter of the looped portion 21 is correctly sized to securely engage the outer diameter of the counter-sink 18 after the tearing strip is removed 40 and when the cover member 17 is used as a reclosure for the opened container 10.

In forming the particular elements described in this container and shown in Fig. 1, it is necessary to first form the container body 10 in the regular manner by properly shaping it to cylindrical or other form and engaging the edges of the blank in the regular side seam 11. This cylindrical or other formed body 10 is then pressed in a beading machine where the first operation of forming the looped construction is accomplished. The forming of the first operation or bead on the container part is clearly illustrated in Fig. 2.

60 The beading mechanism consists of an inner beading roller 23 rotatably mounted on a stud 24 eccentrically secured to the end of a shaft 25, eccentrically journaled in a sleeve 26 rotatable within a shell 27. A hollow cup member 28 is threaded fixedly to

the shell 27 and extends beyond the end of the same as clearly illustrated in Fig. 2. In the annular opening formed in the outer part of the shell there is disposed a ring 29 secured to the cup member 28 by means of 70 screws 30, passing through a hardened steel washer 31 overlying the end of the sleeve 26 and spaced therefrom. The ring 29 is formed with an inwardly extended annular ridge 32 adapted to cooperate at certain 75 periods with an annular groove 33 formed in the roller 23, as clearly illustrated in Fig. 2.

The formed cylindrical container body 10 is inserted within the beading device by being positioned with its scored end against the washer 31, it being understood that the sleeve 26 and the shaft 25 are moved relative to one another, in order, by reason of the eccentricity of each of those members, to position the roller 23 centrally of the ring 29 and away from the inner wall of the ring 29. After the container body 10 has thus been positioned the shaft 25 and the sleeve 26 are both slightly rotated to force the roller 23 toward the inner wall of the ring 29, as illustrated in Fig. 2. In this position the roller 23 engages the inner diameter of the container body 10 and the groove 33 of the said roller forces the material of the container wall against the annular ridge 32 of the ring 29 and causes that part of the container wall to conform to the shape of the ridge 32 and the groove 33. While the sleeve 26 and the shaft 25 is then held in 90 fixed position the shell 27 carrying the cup member 28 and the ring 29 is then rotated, which action causes the ridge 32 to contact the entire circumference of the container body 10 in a circular path of travel, and this action by reason of the cooperation of the roller 23 which works upon the stud 24 forms an inwardly pressed bead 35 into the upper wall of the container body 10 adjacent 95 the tearing strip 13.

After the groove 35 has been formed entirely around the container body 10 the sleeve 26 and the shaft 25 are moved to cause the roller 23 to move inwardly from its position adjacent the ring 29 and thus to free the said container body 10. The formed and now beaded container body is then removed from the beading machine.

The next machine used in the formation of the looped bead of the container 10 is a collapsing and sizing machine, this being clearly illustrated in Figs. 3 to 8 inclusively. This collapsing and sizing machine consists of a clamping head 36 and a collapsing head 37 normally spaced from each other so that the formed and beaded container body 10 can be positioned between the inner extremities of the two head members. As viewed in Fig. 3 of the drawings the clamping head 36 is illustrated on the left hand 105 110 115 120 125 130

side of the drawing while the collapsing head 37 is positioned to the right and in axial alignment with the said clamping head 36. The container 10 is positioned between the two heads, as clearly illustrated in Fig. 3. The clamping head 36 consists of a holding pad 38 threadedly secured to one extremity of a sliding shaft 39 moving horizontally in a stationary frame 40. The said holding pad 38 is provided with a vertical slot 41, as illustrated in Figs. 3 and 8, in which are positioned two clamp fingers 42. The said fingers 42 are normally held outwardly by a coiled spring 43 positioned in a vertical bore 44 formed in each clamp finger 42. Each clamp finger 42 is held from lateral displacement by means of a plate 45, secured by screws 46 to the forward face of the holding pad 38, slots 41 being formed in the said plate to accommodate radial movement of the clamp fingers 42. By this construction the clamp fingers 42 are held outwardly under the tension of the spring 43, and are held for movement within the guideway 41 by the plate 45 (see Fig. 8). The outer face of each clamp finger 42 is formed with an inclined face 47, as clearly illustrated in Figs. 3 and 5. The plate 45 is formed with a corresponding tapered face 48, as illustrated in Fig. 6, and this construction in connection with the inclined face of the clamp fingers 42 permits easy positioning of one end of the formed and beaded container body 10 over the end of the plate 45, the inclined face 48 of the same guiding the container body 10 into the position shown in Fig. 3. The clamp fingers 42 at such time are moved inwardly against the tension of the spring 43 to permit the positioning of the said container body over the ends of the said fingers. By reason of the tension of the spring 43 the container body 10 is thus securely held about the plate 45 and under the clamping action of the fingers 42.

The collapsing head consists of a support ring 49 secured by bolts 50 to a stationary frame 51, positioned opposite the frame 40. The inside diameter of the support ring 49 is just sufficient to accommodate the scored end of the formed and beaded container body 10, as clearly illustrated in Fig. 3. Upon the said container body being positioned into the clamping head 36 as just described the said head is moved toward the right to position the opposite end of the container body 10 within the support ring 49. The end of the container body 10 in this position contacts a collapsing die 52 formed with an annular groove 53, the end of the container fitting within the said groove. Said collapsing die is carried upon a sliding hollow shaft 54, which is adapted to be operated by a suitable connection not shown. Slidably positioned within the hollow shaft 54 is a sliding shaft 55, actuated by a suitable connection not shown, the inner extremity of the said shaft 55 being threadedly connected to a forming and sizing disc 56, the outer diameter of which is of sufficient size to engage the inner diameter of the bead 35 formed in the container body 10. The forward outer edge of the said forming disc 56 is rounded as at 57 to permit easy insertion of the disc 56 within the container groove 35, during the collapsing operation.

With the clamping head 36 and the collapsing head 37 in the position illustrated in Fig. 3 the container body 10 is firmly held between the face of the holding pad 38 connected with the clamping head 36 and the face of the collapsing die 52, connected with the collapsing head 37. Reforming of the bead 35 in the collapsing operation takes place by reason of movement of the collapsing die 52 the same being moved toward the left by movement of the hollow shaft 54. Inasmuch as the groove 35 forms the weakest part of the container wall the said groove must give way under the collapsing action. Previous to the movement of the collapsing die 52 the disc 56 has been inserted on the inside of the inner diameter of the groove 35 of the container 10, this position being illustrated in Fig. 3. The particular form taken by the groove 35 of the container body 10 is dependent upon the relative movement between the disc 56 and the collapsing die 52 during the collapsing operation. If the looped form illustrated in Fig. 1 of the drawings is desired, this being the form illustrated in the patent to Young previously referred to, the forming and sizing disc 56 is held in a stationary position during the movement of the collapsing die 52. This resulting form of loop 58 and the relative position of parts of the collapsing head 37 after the collapsing action, is illustrated in Fig. 4 of the drawings. Variations in the shape of the loop will be more fully set forth after the full operation of the collapsing and sizing machine has been described.

After the double loop 58 has been fully formed the collapsing die 52 is moved toward the left, as viewed in Figs. 3, 4 and 5, carrying the container body 10 from within the support ring 49 and stripping the bead 58 off of the outer surface of the disc 56, this final position being illustrated in Fig. 5. Simultaneously with the movement of the collapsing die 52 the shaft 39 carrying the holding pad 38 of the clamping head 36 is also moved toward the left.

The clamping head 36 also consists of the following parts in addition to those previously described:

A stripper ring 59 is provided with an annular flange 60, positioned over the small diameter of the holding pad 38, as clearly illustrated in Figs. 3 and 6. The said stripper ring 59 is retained in position surround-

ing the pad 38 by means of a washer 61 secured by screws 62 to the back face of the holding pad 38. Projecting fingers 63 are extended from the face of the stripper ring 59 and these fingers operate in slots 64 formed in the forward flange of the holding pad 38 and in slots 65 formed in the outer extremity of each of the clamp fingers 42. The forward face of the fingers 63 normally projects in a plane with the forward face of the holding pad 38 and in this position rests against the edge of the container body 10, (see Figs. 3 and 5). After the clamping head 36 is moved toward the left preparatory to stripping the container body 10 from the collapsing and sizing mechanism the rear face of the stripper ring 59 first strikes against the frame 40, this position being shown in Fig. 5. The container body 10 is then completely released from the holding device in the collapsing mechanism by the simultaneous retraction of the collapsing die 52 moving toward the right and by the movement of the holding pad 38 and clamp- 25 ing fingers 42 toward the left, this action being accomplished through the medium of the shaft 39. Inasmuch as the stripper ring 59 is prevented from moving toward the left the clamp fingers 42 and the face of the holding pad 38 are withdrawn from within the container body 10, this action resulting in freeing the said container body 10 from the clamp fingers 42 and the collapsing die 52, this position being shown in Fig. 6. 35 In the machine of my present invention, by a simple change in relative movement between certain parts I am able to control at will the particular shape of the looped construction without adding any further mechanism or without interfering in any way with the resulting friction wall seat formed in the container body.

As clearly shown in Figs. 9, 10 and 11 the shape of the particular loop formed by the collapsing action can be varied according to the relative movement of the forming and sizing disc 56 and the collapsing die 52 during the collapsing operation. As shown in Fig. 9 the container body 10 is inserted in the regular way, the forward face of the supporting ring being in line substantially with the forward face of the sizing disc which has been moved by the shaft 55 prior to the movement of the die 52 to a position on the 50 interior of the inner diameter of the groove 35 of the container 10. If upon movement of the die 52 the disc 56 is moved a slight distance so that its forward face projects slightly beyond the forward face of the support ring 49, the form of loop produced is of a symmetrical double loop shape, illustrated at 66 in Fig. 10.

If on the other hand, the disc 56 is moved forward in unison with the travel of the collapsing die 52 so that the forward face of

the disc 56 projects at a greater distance in front of the face of the support ring 49, the resulting loop 67 (Fig. 11) is one directly opposed to the loop formed in the first described manner, and shown in Fig. 1. 70 It should be evident that any intermediate shape of the loop can be obtained by changing the relative travel of the loop forming and sizing disc 56 and the collapsing die 52.

It is thought that the invention and many of its attendant advantages will be understood from the foregoing description, and it will be apparent that various changes may be made in the form, construction and arrangement of the parts without departing 80 from the spirit and scope of the invention or sacrificing all of its material advantages, the form hereinbefore described being merely a preferred embodiment thereof.

I claim:

1. In an apparatus of the character described, the combination of a support, a clamping head comprising a holding member, means for shifting the same, clamping fingers carried by said holding member and arranged to receive the can body end thereover and to hold the same rigidly and a stripping member carried by said clamping head, and movable relatively thereto, said stripping member having means for engaging the can body end and forcing it from said clamping fingers.

2. In an apparatus of the character described, the combination of a support, a clamping head comprising a holding member forming a shoulder to receive the can body end, means for shifting said clamping head, clamping fingers carried by said holding member and arranged to receive the can body end thereover and to hold said end rigidly against said shoulder and a stripper member mounted on said clamping head and shiftable relatively thereto said member including a plurality of fingers adapted to engage the can body end and eject it from said clamping head.

3. In an apparatus of the character described, the combination of a support, a collapsing head and forming disc adapted to receive therebetween a can body end with a peripheral bead, a die having an annular seat for said can body end, a clamping head having a holding member provided with spring pressed fingers and a shoulder adapted to receive the opposite end of said can to hold the same, a stripper ring on said clamping head, and means for shifting said die and clamping head for deforming said bead and for stripping said can from said collapsing head and clamping head.

4. The method of forming an inwardly looped wall in a cylindrical wall, comprising subjecting a cylindrical wall, while held against outward bending, to endwise pressure while maintaining a predetermined cir-

85

130

136

cumferential zone thereof between concentrically disposed dies maintained a fixed distance apart.

5. The method of forming an inwardly looped wall in a cylindrical wall, comprising forming a peripheral bead in the container wall and collapsing the bead by endwise pressure while simultaneously holding the wall from outward bending and limiting the 10 inward bending to a predetermined circumference.

6. The method of forming a looped wall in a cylindrical wall comprising forming a peripheral bead in the container wall, holding 15 said wall from outward bending, and collapsing the bead against an unyielding circular wall of an exact circumference while controlling movement of the bead wall in other directions.

20 7. The method of forming a looped wall in a cylindrical wall comprising forming a peripheral bead in the wall of a container, and collapsing the bead between concentrically spaced apart rigid die surfaces and 25 bending the collapsed bead toward the end of said wall.

8. The method of forming a looped wall in a container wall comprising collapsing a 30 preformed peripheral bead in the container wall by endwise pressure on the container wall while maintaining the bead against an inner circumferential wall of predetermined diameter whereby to form a wall portion of said collapsed bead of such predetermined 35 diameter and bending said collapsed bead toward the end of the container.

9. The method of forming a looped wall in a cylindrical wall comprising subjecting 40 a cylindrical body wall to endwise pressure while maintaining a predetermined circumferential zone thereof between concentrically disposed dies maintained a fixed distance apart, and causing the inner die to move 45 endwise relatively to the pressure means during such endwise pressure.

10. The method of forming a looped wall in a cylindrical wall comprising forming a container wall within an inwardly projecting bead, deforming the bead so as to restrict 50 radially inward movement thereof, while causing predetermined endwise bending of the bead wall to form a looped wall of desired shape.

55 11. The method of forming a looped wall in a cylindrical wall comprising forming a peripheral bead in a container wall, subjecting the container wall to endwise pressure while disposing the bead between two concentric die surfaces, maintained a predetermined distance apart, but movable relatively in parallel planes, and controlling such relative movement of said die surfaces and of the pressure means to determine the shape 60 of the looped portion formed.

65 12. The method of forming a looped wall

in a cylindrical wall comprising forming a peripheral bead in a container wall, subjecting the container wall to endwise pressure while disposing the bead between two concentric die surfaces maintained a predetermined distance apart and thereby forming a loop in said wall and bending said loop toward one end of the can.

13. In an apparatus of the character described, the combination of a support, for 75 holding a cylindrical body having a peripheral bead in its wall, means for subjecting the container wall to endwise pressure and forming a loop therein and means for simultaneously shaping the loop to a predetermined circumferential dimension and inclining it toward the end of said body.

14. In an apparatus of the character described, the combination of a support for 80 supporting a cylindrical body having a peripheral bead between two concentric die surfaces spaced apart, means for subjecting the body wall to endwise pressure and means for causing the inner die surface to move 85 relatively to said pressure means.

90 15. In an apparatus of the character described, the combination of a support, an outer stationary ring forming a die, a forming means concentrically disposed within said ring and spaced from its inner circumference, a die concentrically disposed in said space and movable therein, said die having an annular groove to receive a cylindrical wall of a body having a peripheral bead 95 adapted to lie in said space between said ring and forming means, and means for shifting said die through said space and relative to said forming means to subject said body wall to endwise pressure.

100 16. In an apparatus of the character described, the combination of a support, a ring like means constituting a die, a forming means concentrically located within said ring and spaced therefrom, a die shiftably and concentrically mounted in said space and 105 provided with a seat for the cylindrical wall of the container body and means for shifting said die relative to said forming means to subject the body wall to endwise pressure so as to deform and loop the body wall in the 110 space between said ring and forming means.

115 17. In an apparatus of the character described, the combination of a support, means comprising concentric die surfaces maintained a fixed distance apart, means for rigidly supporting a cylindrical body with a predetermined circumferential zone thereof disposed between said die surfaces and means for exerting predetermined, endwise pressure 120 on the body wall to deform the wall between said surfaces, and to bend the deformed part of the wall toward the end of said cylindrical body.

125 18. In an apparatus of the character described, the combination of a support, a col- 130

lapsing head mounted thereon, a forming disc concentrically disposed thereon and spaced from the inner wall of said head to form an annular seat for the can wall and can bead, a die concentrically disposed in said space and having an annular groove to receive the end of the can wall, a rigid support for the opposite end of the can wall, means for shifting said die relative to the forming disc and means for shifting said forming disc.

19. In an apparatus of the character described, the combination of a support, a clamping head for rigidly holding one end 15 of the can body, a collapsing head, a forming disc disposed concentrically in said collapsing head and spaced therefrom, said disc having a shaft for shifting said disc, a die adapted to move in the space between said 20 head and disk and having an annular seat for the can end, said die having a tubular shaft concentrically surrounding the shaft

of said disc and means for moving said shafts.

20: The method of forming a looped friction seal seat in a cylindrical container wall comprising collapsing a single loop bead formed in the wall of a container by subjecting the container wall to endwise pressure, while maintaining the bead between concentrically spaced apart rigid die surfaces and causing said die surfaces to move relatively in parallel planes to reshape said bead into a double looped bead of predetermined shape and dimension. 25

21. The method of forming a looped friction seal seat in a cylindrical container wall comprising forming a container wall with an inwardly projecting single bead and deforming said bead and restricting radial inward movement thereof, whereby to produce a double looped seat portion of predetermined dimension in said container wall. 30 40

GEORGE FREDRICK WALTER.
